UNITED STATES PATENT OFFICE

EINAR MORTERUD, OF TORDEROD, NEAR MOSS, NORWAY

CIRCULATION SYSTEM FOR PULP DIGESTERS

Application filed November 14, 1928, Serial No. 319,390, and in Norway December 23, 1927.

In the process of digesting pulp it is well known that it is necessary to circulate the digester liquor in order to establish even temperature conditions so as to obtain throughout the pulp charge the best conditions for releasing and dissolving the incrustations.

When the circulation takes place through a pump on the outside of the digester, it is known to provide the circulation conduit with a valve arrangement adapted to reverse the direction of circulation, whilst maintaining the direction of rotation of the pump.

It has also been suggested to mount the circulation pump inside the digester in order to obtain a cheap, valveless arrangement.

This arrangement of the pump inside the digester, however, has the drawback of not permitting reversion of the direction of circulation. The arrangement of valves which will enable the direction of circulation to be reversed is out of question for practical reasons when the pump is mounted inside the digester, and in order to obtain the advantages of the pump arrangement inside the digester whilst at the same time also obtaining the advantages of reversible circulation, the digester is provided in accordance with the present invention with a reversible circulation pump mounted inside the digester and provided with a conduit leading to the top of the digester, and another leading to the bottom thereof, each of said conduits being adapted to act as intake and outlet tube respectively according to the direction of rotation of the pump.

Both conduits consequently are provided with sieves or screens in order to prevent pulp from entering into the pump.

The accompanying single figure shows one form of the invention.

On the inside of the digester shell 1 there is mounted a reversible pump 2 of any conventional type adapted to be driven in both directions by means of an exterior transmission element 3, such as a pulley or the like.

The suction and pressure tubes respectively 4 and 5 of the pump 2 are both provided with sieve arrangements 6.

During the rotation of the pump in one direction tube 5 will act as suction and tube 4

as pressure pipe, and the circulation will follow the arrow 1.

When the pump rotates in the opposite direction, tube 4 will be suction pipe and tube 5 pressure pipe, and the circulation will follow the arrows 11.

Claims.

1. In a pulp digester a reversible circulation pump mounted inside the digester, circulation tubes leading from said pump to the top and bottom respectively of the digester and screens covering the outlet openings of said circulation tubes into the digester in order to prevent wood pulp from entering the tube which is acting as suction tube to the pump.

2. In a pump digester, means for producing a reversible circulation, said means being comprised substantially entirely of a reversible circulation pump mounted inside the digester, circulation tubes leading from said pump to the top and bottom respectively of the digester, and screens covering the outlet openings of said circulation tube into the digester in order to prevent wood pulp from entering that tube which is acting as the suction tube of the pump.

In testimony whereof I affix my signature.
EINAR MORTERUD.
